UNITED STATES PATENT OFFICE.

WILLIAM PHILLIPS, OF CHICAGO, ILLINOIS.

FLYING-MACHINE.

No. 856,910.

Specification of Letters Patent.

Patented June 11, 1907.

Application filed August 1, 1905. Serial No. 272,148.

To all whom it may concern:

Be it known that I, WILLIAM PHILLIPS, a citizen of the United States, and a resident of Chicago, in the county of Cook and State of Illinois, have invented a new and Improved Flying-Machine, of which the following is a full, clear, and exact description.

This invention relates to a class of machines designed for travel in the air, and has for its object to provide novel details of construction for a machine of the character indicated, which are simple and practical and enable the navigation of the air in any direction.

The invention in brief embodies a car, a plurality of peculiarly constructed wings mounted on the car, novel means for communicating motion to and controlling the adjustments of the wings for effecting progressive movement in any direction, a guiding vane, and means for changing the position of the vane from the interior of the car.

The invention further consists in the novel construction, combination and arrangement of parts as is hereinafter described and defined in the subjoined claims.

Reference is to be had to the accompanying drawings forming a part of this specification, in which similar characters of reference indicate corresponding parts in all the figures.

Figure 1 is a perspective view of the complete machine; Fig. 2 is an enlarged, partly sectional side elevation of the machine, taken through its longitudinal axis, the wings being broken away; Fig. 3 is a partly sectional side view of the lower portion of the car, and the leg attachments therefor, the section being substantially on the line 3—3 in Fig. 2; Fig. 4 is an enlarged sectional side view of the lower portion of the wing-actuating gearing employed; Fig. 4^a is an enlarged, broken and sectional side view of the upper portion of said driving gearing for the wings; Fig. 5 is a plan view of the frames of the duplicate pilot wings showing their construction and arrangement; Fig. 6 is a plan view of the frames of the lower wings showing their construction and arrangement; Fig. 7 is a partly sectional fragmentary side view of frame portions for the pilot wings, an upper portion of a wing supporting and driving shaft, and means for bracing the shaft and the wings thereon; Fig. 8 is a side view of a car seat, of a windlass, and cords wrapped on the windlass for controlling a steering vane;

Fig. 9 is a partly sectional side view of an upper portion of a car-frame and of a motor-frame, showing a slightly modified means for hinging the motor-frame on said car-frame; 60 and Fig. 10 is a fragmentary side view of a portion of a steering vane and the support therefor, that is a detail of the invention.

The car wherein the operator is housed also carries means for its movement through 65 the air in various directions, said means being hereinafter more fully described.

The supporting car is preferably formed with a frame comprising a circularly edged bottom plate 10, provided with a peripheral flange *a* projected upwardly. On the bottom plate, at suitable intervals, a plurality of similar frame strips 10^a are secured by their lower ends, and thence extend upward in parallel planes. Said strips are of any 75 suitable light yet strong material, having a length sufficient to permit a person to stand upright in the car after the introduction of other details. Two of the frame-strips 10^a that are opposite each other, are formed of 80 thin steel or other strong metal, and are designed to sustain the main portion of weight and strain imposed upon the car frame. These strips and the other frame strips are bent toward a common center, and at their 85 inner ends are secured upon a metal ring, not shown. The said two metal frame strips are reinforced by two transverse brace bars 10^b, 10^c, which are of suitable metal or may be of wood, the cross bar 10^b being joined to the 90 upright frame-strips 10^a at the points where they join their overhead arched members as shown in Fig. 2, the other cross-bar 10^c being secured by its ends a proper distance below the bar 10^b and parallel therewith. 95

A turntable 10^d is provided, of slightly greater diameter than the bottom-plate 10, and at its edge a hook flange *a'* is turned upward and inward so as to have a rotatable engagement with the flange *a*, as shown in Fig. 2. Centrally in the bottom plate 10 and turntable 10^d, registering apertures of circular form are produced, wherein is fitted a depending cylindrical collar *b* that projects downward from a bottom piece *b'* that is the 105 lower end of a tubular seat 10^e and whereon said bottom piece is secured; and as appears in Figs. 2 and 3, the collar *b* is firmly secured in place on the turntable after a series of 110 antifriction balls *b'* are introduced in opposite circular grooves formed in the bottom piece *b'* and turntable 10^d.

The flying apparatus consists of two sets of wings each set being differently shaped and rotated oppositely, one set above the other. The upper wings 11 of a similar form are preferably two in number, it being understood that a greater number may be employed, but as all extra weight is objectionable the best results are had with the preferred number. Each wing 11 is peripherally 5 segmental, as indicated in Fig. 5, where they are shown in plan and appear as joined together, but in fact are separated by the spindle or shaft 11^a whereon they are oppositely mounted. The spindle 11^a is formed 10 of thin tubular metal or other available material, and is of a sufficient length for effective service as a support and driving shaft for the upper pair of wings. Each wing 11 is composed of a skeleton frame comprising 15 the following members: three collars *c* are mounted upon the spindle 11^a and secured thereto at proper distances apart, the upper collar being suitably spaced from the upper end of the spindle and on the latter below 20 the lowermost collar *c* a spider *c'* having a hub, radial arms and a circular peripheral ring is secured as indicated in Fig. 7; and as represented in said figure, a conical casing 11^b is fitted upon the upper portion of the 25 spindle 11^a, having its lower edge affixed upon the spider ring *c'* and converging to the upper end of said spindle, whereon the casing is secured by suitable means.

As a means for stiffening the upper portion 30 of the spindle 11^a and the casing 11^b, that may be of fibrous or other light strong thin material, a plurality of light, strong, tie strips or cords *d* extend from the collars *c* to the spider ring *c'*. From each of the collars 35 *c* radially extend two ribs *c'* in substantially opposite directions, the ribs at one side of the collars being portions of the frame for one wing, and those at the opposite side corresponding rib members for the other upper wing. On the ribs for one wing 11, a series 40 of spaced and curved bows *c*³ are secured, these bows that are formed of elastic ratan or other suitable material, being arranged concentrically to each other, and gradually 45 lengthened so as to project about an equal distance from the radial ribs that are outermost, and upon the ends of the bows *c*³ and the outer ends of the ribs *c'*, a border flange *c'*⁴ of thin metal plate is secured concentric with the bows. It is to be understood that the 50 collars *c* are so adjusted on the spindle 11^a that the ribs *c'* will be disposed in spiral order, so that when the frame of each wing 11 is covered with a suitable fabric 11^c each 55 wing will appear as the segment of a screw, the pitch or spiral trend of one blade or wing being opposite from that of the other wing.

The covering 11^c for the wings 11 may be of silk or other strong, light fabric, that is 60 stretched taut over the frame of each wing

on their under sides, and the fabric may be reinforced over the ribs *c'* by securing strips of light, strong fabric on the covering above said ribs, not shown. To give proper form to the wings, a series of guy-wires or cords *e* 70 are affixed by one end of each upon the flange *c'* and thence are extended to respectively have their outer ends secured upon the ribs *c'*, which latter are drawn by the guys so as to render the lower surface of each wing 75 concave, and the upper surface correspondingly convex.

It will be seen in Fig. 1, at the right side, that the corners on the outer ends of the wings 11 may be rounded somewhat if this is 80 preferred, the border flange *c'* being properly shaped to effect this, and it will be obvious that these wings which simulate the shape of those of a large bird, will have a powerful lifting effect when the spindle 11^a 85 is quickly rotated in the direction of the curved arrow in Fig. 1. The lower set of wings 12, four in number, are of similar shape and construction as will be hereinafter described, the means for mounting these 90 wings upon the spindle 11^a consisting of the following details, which appear in Figs. 2, 4 and 4^a. A light sheet metal drum is provided having a cylindrical side wall *g* preferably less in diameter than that of the flange 95 or ring *c'* on the spindle *c*, the upper end of said drum being closed by a flat head plate *g'*. A tubular shaft 13 having a true bore is loosely mounted upon the spindle 11^a and passes through the center of a collar *g*³ that 100 is secured thereto near the upper end thereof, the shaft extending a proper distance below said collar, said collar resting on the head wall *g'* of the drum *g*. Between the upper end of the tubular shaft 13 and the top wall 105 or head plate *g'* of the drum, a roller bearing *g*⁴ is introduced, the rollers thereof bearing upon the spindle 11^a, and holding it spaced from the shaft 13. A motor supporting frame consisting of a plurality of spaced upright bars *h* that are joined to a spider *h'* having a central hub *h*², is held concentric with the hollow shaft 13, by the loose insertion of said shaft through the hub as shown in Figs. 2 and 4^a, the spider having a collar thereon adjacent to the hub *h*², and a ball bearing is 115 placed between the opposed faces of the collar and hub, as shown in Figs. 2 and 4^a. Below the hub *h*², on the frame members *h*, projections *h*³ are formed or secured, and between said projections and the lower side of the hub a roller bearing *h*⁴ is held, the rollers of which have peripheral contact with the cylindrical body of the tubular shaft 13. A bevel gear *k*¹ is secured upon the shaft 13, that 120 faces downwardly, and between the upper side of said gear and the projections *h*³ a ball bearing is introduced, as is clearly shown in Fig. 4^a. The lower end of the motor frame is preferably closed by a pan *h*⁵, for catching 125 130

any drippings that may fall from a motor of any preferred construction, located and secured in the supporting frame just described. A hinged connection is formed between the lower end of the motor holding frame and the cross bar 10^b on the frame of the car hereinbefore described. Said connections may be as shown at *i* in Fig. 2, which permits the motor supporting frame to be rocked in opposite directions so as to assume inclined positions, one of which is indicated by dotted lines in Fig. 2 at the right. It is preferred however, to connect the motor supporting frame on the cross bar 10^b by a double hinge as indicated at *i'* in Fig. 9, which permits the motor frame to be rocked in four directions instead of two, which will enable the more perfect operation of the wings of the machine, as will be further explained hereinafter. A radial flange *k* is formed or secured upon the lower portion of the spindle 11^a whereon the lower extremity of the tubular shaft 13 seats and is supported to rotate, and immediately above said flange a bevel gear *k'* is secured upon said shaft 13, having its toothed face lowermost, as is shown in Figs. 2 and 4. Upon the portion of the spindle 11^a that extends below the lower end of the shaft 13, an annular swivel block *m* is loosely mounted, carrying roller bearings *m'* and *m''*, that respectively have contact with the exterior of the shaft 13 and with the spindle 11^a, as shown clearly in Fig. 4. From one side of the swivel block *m* a short journal shaft *m'* projects, whereon a bevel gear *k''* is mounted free to rotate, said gear meshing with the upper bevel gear *k'*. A preferably similar bevel gear *k''* is secured upon the spindle 11^a, below the block *m*, and meshes with the bevel gear *k''*, as shown in Fig. 4. The spindle 11^a projects below a collar *k'* thereon, and on said end a conical point is formed, this point having a seat in a cupped bearing formed in a cross bar *k* that is secured by its ends to opposite members *h* of the car; and it will be obvious that this support for the spindle greatly reduces frictional resistance to its rotation if the cup bearing is properly lubricated. As the hollow shaft 13 is held concentric with the axis of the spindle 11^a by the roller bearings *H'* and *m'* without other lateral contact, this serves to reduce friction between said parts to a minimum degree. Upon the hub of the bevel gear *k'* which projects outwardly, a sprocket gear *k''* is secured that may be connected with a similar wheel on a motor held in the motor frame already described, so that by the operation of the motor not shown, the shaft 13 and spindle 11^a will be rotated oppositely by the geared connections specified.

Referring to the wings 12, shown in Figs. 1, 2 and 6, these are essentially fan-shaped, and are each constructed with a skeleton frame, consisting of a plurality of ribs *n* that radiate

from the cylindrical wall *g* and are held 65 spaced apart by a series of curved bows *n'* that are disposed concentrically with the wall of the drum *g* and with each other, the ends of the bows and outer bow being strengthened by a reinforcing border flange *n''*. The 70 four wings 12 are disposed oppositely in pairs, and as shown in Figs. 1 and 2 have a similar dip or downward inclination, and also a diagonal trend of like degree where they join the cylindrical wall *g*, thus giving 75 the wings a similar screw twist to that had by the blades of a marine propeller. The skeleton frames of the four wings 12 are covered with light, strong fabric properly stretched and secured thereon, and each wing is held 80 against lateral displacement by the braces *o*, that may be thin strips of any suitable material, fastened at their ends upon the outer ends of the wings. As before mentioned the wings 12 are rotated in a direction opposite 85 from that given to the upper wings 11, that is to say, as is indicated by the arrow *x* in Fig. 1, and it is essential that the area of the four wings should be so proportioned to the upper wings 11 that the tendency to rotate 90 the entire machine about the spindle 11^a as an axis will be neutralized.

An important feature of this improvement is the provision for alighting and maintaining the machine in an upright position while not 95 in use, this comprising four legs 14 that not only serve as a base for the apparatus, but also are utilized as a means for supporting and adjusting a steering vane 15. The legs 14 may be formed of light metal tubing and 100 are hinged upon the lower side of the turntable 10^d at four equally distant points as indicated at *p* in Figs. 1 and 2, two of said legs also appearing in Fig. 3. The leg designated by a reference character *r* is the forward one, 105 *r'* are two opposite side legs, and *r''* represents the rear leg, and as shown, all the legs are limited in outward movement by stay rods *r'* that extend down from the turntable 10^d and at their lower ends are attached to 110 collars *r''* which are respectively mounted and may be secured at suitable points on the legs or be permitted to slide thereon. The two legs *r'* are controlled in their rocking movement by means of two levers *v* that are 115 extended upward into the hollow seat 10^e and are crossed and pivoted where they have lapped engagement as shown in Fig. 3. The diverging upper ends of the levers *v* are pivoted upon similar ends of two link rods *v'* 120 which pass freely through opposite openings in the side wall of the seat 10^e. The lower ends of the levers *v* are pivoted upon the similar ends of two connecting rods *v''* that at their remaining ends are pivoted upon the 125 side legs *r'*, and to enable these legs to receive rocking adjustment by manipulation of the link rods *v'* by a person in the car, the collars

r^5 may be allowed to slide on the legs r' . Upon the front leg r preferably above the collar r^5 thereon, one end of a frame rod s for the vane 15 is pivoted, said frame rod extending laterally and rearwardly from the front leg of a suitable length for its effective service as a portion of the vane, the rod lapsing upon the rear leg r^3 is pivoted upon a 5 slidable collar r^3 that is mounted upon the rear leg as shown in Fig. 2. A similar frame rod u is pivoted by one end on the front leg r at a suitable point below the upper frame rod s , and thence extends rearward across the rear leg r^3 whereon it is slidably secured as 10 clearly shown in Fig. 10, this loose connection comprising a collar u' loosely mounted upon the rear leg r^3 and a similar collar u^2 loosely mounted upon the lower frame rod u , these collars u' , u^2 being pivoted together 15 where they have lateral contact, this connection of the swiveling collars permitting the lower frame rod of the vane to slide endwise in the collar u^2 and also be adjusted longitudinally of the rear leg r^3 by a sliding movement of the collar u' thereon.

The frame rods s and u are spaced apart by thin light but rigid cross bars that are indicated by dotted lines in Figs. 1 and 2, and the main portions of the frame thus produced are 20 covered with a suitable fabric that completes the blade of the vane as is shown in said figures. Upon the lower extremity of the rear leg r^3 a sheave wheel w is mounted loosely, and on said sheave wheel the bight of a doubled cord or other light, strong flexible connection is placed, the two runs w' , w^2 of the 25 cord or rope being extended upward across the frame rods u and s , and thence through the collar b into the hollow body of the 30 seat 10° .

A windlass is mounted on the seat wall 10° , occupying an opening therein, and on the roller shaft t of said windlass the ends of the two runs w' , w^2 of the doubled cord or rope 35 are secured near the ends of said shaft, and thence are wrapped in opposite directions thereon, so that these runs of cord that extend upward from the sheave wheel w when the roller shaft t is rotated will be respectively wrapped thereon and unwrapped 40 therefrom. It will be seen that by means of the windlass and doubled cord just described, the vane blade may be rocked upwardly or be permitted by its gravity to incline more or less downwardly as the proper control of the 45 flying machine may require. Furthermore it will be evident that the fixture of the hollow seat post 10° upon the turntable 10° and the loose connection of the edge of the latter 50 with the bottom plate 10 of the car frame, enables an operator who is seated upon the post 10° to turn the latter in either direction, and with it the blade of the vane 15 , by a 55 turning movement of his body. The car

frame is apertured in its side for the entrance 60 and exit of an operator, the door opening being closed by a skeleton door frame, represented in Fig. 2, and the car body frame and door frame are covered with suitable fabric, or thin sheet metal if this is preferred, thus 65 excluding the elements.

One means for inclining the motor frame and wings 11 , 12 at any desired angle from a perpendicular position is shown in Fig. 2, 70 consisting of a plurality of tackle ropes l and blocks l' that are connected at suitable points with the upper portion of the motor frame, and the ropes that engage the sheaves of the blocks extending down into the car, may be lashed fast to projections on the car frame 75 to secure the motor frame as adjusted. As shown in Fig. 2, a ladder may be provided to facilitate access to the motor to be placed in the car frame as hereinbefore specified.

In operation, assuming that the actuating 80 mechanism held in the rockable motor frame, is capable of developing sufficient power for the rotation of the wings 11 , 12 at a desired speed, it will be seen that if the spindle 11^a is given a perpendicular position, the rotation of the wings 11 , 12 in opposite directions as is indicated by the curved arrows in 85 Fig. 1, will cause the wings to lift the machine as an entirety until a desired height is attained. If it is desired to travel laterally in a certain direction, the motor frame and wings carried thereon, are inclined a proper degree by an adjustment of the tackle ropes l , and thus adapt the wings to exert a pull in the direction toward which the 90 spindle 11^a inclines, it being of course understood that the adjustment of the steering vane 15 adapts said vane to co-act with the wings for giving the machine a desired direction. When a descent of the flying machine 95 is desired, it is only necessary to reduce the speed of rotation of the wings 11 , 12 , thus permitting the force of gravity to gradually overcome the ascending force of the wings, so that the apparatus may be gently lowered 100 to the ground. When the machine is descending, the operator manipulates the windlass so as to pull upon the run w^2 of the doubled cord wrapped on the roller shaft of 105 the windlass, which will force the front leg r outward. The side legs r' are also spread apart by manipulation of the link rods v' in 110 an obvious manner, so that a wide base is provided by the outwardly inclined legs for the stable support of the flying machine in 115 an upright position on the ground or other level base.

While the preferred use of the improved 120 machine is for navigation of the air by a passenger carried in the car of the apparatus, it is also contemplated to so arrange the size of the device and relative proportion of parts that it may be operated as a toy, and

the motive power in this case may be a coiled spring.

Having thus described my invention, I claim as new and desire to secure by Letters

5 Patent:

1. A flying machine embodying wings supported centrally on an essentially upright spindle, said wings having segmental spiral form and extending in opposite directions, each wing comprising a plurality of ribs extended in spiral order radially from collars secured on the spindle, a plurality of laterally curved bow strips secured transversely on the ribs, a border flange extended around the frame, and a cover stretched taut on each frame.
- 10 2. An air ship comprising a casing for supporting a motor, a shaft connected therewith, said shaft being provided with lifting vanes, a frame pivotally supported below the motor casing, means connected with the motor casing whereby to swing the frame at an angle with respect to said motor casing, a rotatable turn table connected with the frame and having a seat projecting into the frame, a vane connected with the turn table, means for swinging and lowering the vane, and legs connected with the turn table for supporting the frame when in an active position.
- 15 3. A flying machine comprising wings supported centrally on a spindle, said wings having a segmental spiral form and extending in opposite directions, each wing comprising ribs extending in spiral order radially from the spindle, bow strips secured transversely on the ribs, and a cover stretched on the ribs.
- 20 4. A flying machine comprising wings supported centrally on a spindle, said wings having segmental spiral form and extending in opposite directions, and each wing comprising a plurality of ribs extending in spiral order radially from the spindle, and a cover connected with the ribs.
- 25 5. A flying machine embodying a framed car, a motor frame rockably mounted on the upper portion of the car frame, a spindle mounted upon the motor frame, a hollow

shaft mounted on the spindle, means for rotating the hollow shaft and the spindle in opposite directions, means for inclining the motor frame, spindle and shaft together in a desired direction, two segmental dished wings secured oppositely on the spindle, said wings having spiral trend in the same direction, and four segmental spirally twisted wings mounted on the hollow shaft and inclining in a direction opposite from the spiral trend of the upper paired wings.

6. A flying machine embodying a framed car, a turntable rotatable on the bottom of the car frame, adjustable legs on the lower side of the turntable, and means for adjusting said legs from the interior of the car.

7. A flying machine, embodying a car frame, a turntable rotatable on the bottom of the car frame, a plurality of legs hinged by one end of each on the bottom of the turntable, means for turning the table from within the car frame, a steering vane supported on the legs extending laterally therefrom, and means for raising or lowering the outer end of the vane, said means being controlled from within the car frame.

8. A flying machine embodying a skeleton car frame, a turntable held to rotate at its edge on the bottom wall of the car frame, a hollow seat post in the car frame having a collar passing down through an opening in the bottom of the car frame and secured in a registering opening in the turntable, legs hinged by one end on the lower side of the turntable, a steering vane adapted for rocking movement on the legs, means for rocking the vane in a vertical plane from within the car frame, and means for rocking two opposite legs from within said car frame.

In testimony whereof I have signed my name to this specification in the presence of two subscribing witnesses.

WILLIAM PHILLIPS.
